(57) **CLAIM**

The ornamental design for an LED infrared skin-treatment device, as shown and described.

DESCRIPTION

FIG. 1 is a front-elevational view of an LED infrared skin-treatment device showing my new design;

FIG. 2 is a left-side elevational view of the device of FIG. 1;

FIG. 3 is a right-side elevational view of the device of FIG. 1;

FIG. 4 is a rear-elevational view of the device of FIG. 1;

FIG. 5 is a top plan view of the device of FIG. 1;

FIG. 6 is bottom plan view of the device of FIG. 1; and,

FIG. 7 is a perspective view of the device of FIG. 1.

The broken lines show portions of the LED infrared skin-treatment device that form no part of the claimed design.

1 Claim, 6 Drawing Sheets
